FIG. 9

UNITED STATES PATENT OFFICE

ADON L. SMITH, OF ROCKY RIVER, OHIO, ASSIGNOR TO THE GUARDIAN SAFE AND MANUFACTURING COMPANY, OF ALLIANCE, OHIO, A CORPORATION OF OHIO

SAFE CONSTRUCTION

Application filed August 29, 1928. Serial No. 302,700.

It is an object of this invention to provide a safe that shall be proof against opening without the use of the lock mechanism, either by a combination or suitable key. The same is attained by the provision of suitable mounting for the locking bolts whereby such mechanism is blown off from the door when a charge of explosives is fired within the door and outside of such mechanism. The force of the explosive will therefore, force the mechanism inwardly towards the center of the receptacle such as a safe.

The object of this invention is to lessen the risk of safe breaking, and is attained by mounting the several links detachable upon the lock bolts, so that said links will be easily detached by an explosive, a thin metal plate being secured over the inner surface of the door to normally hold the links in operative position. These and other objects and details of the invention will be more fully described in the following specification, set forth in the appended claims and illustrated in the accompanying drawings, in which:

25 Figure 1 is a face view of the safe door shown in its closed position;

Figure 2 is a central transverse section in a plane indicated by the line 2—2 of Fig. 1;

30 Figure 3 is a section taken in the plane indicated by the line 3—3 of Fig. 2;

Figure 4 is a section taken in the line 4—4 of Fig. 3;

Figure 5 is a transverse section on the line 5—5 of Fig. 3;

35 Figures 6 and 7 are perspective views showing the upper and lower faces, respectively, of the bolt actuating disc;

Figure 8 is a perspective view of one of the actuating links;

40 Figure 9 is a detail view of one of the locking pins, and

Figure 10 is a perspective view of one of the locking bolts.

45 The wall of the receptacle is shown as provided with a safe door 10 which includes therein the door cone 11 designed to normally fit within the cone opening 12 of the wall of the receptacle and the door is mounted upon the receptacle by means of a metal rim 13 having ears 14 extending in parallelism for

engagement with ears 15 upon the receptacle frame. Such receptacle may be a vault or other form of safe. Within the door is provided the conventional cavity of cylindrical form 16. The door carries a series of locking bolts 17 which, when the door is closed engage the receptacle walls, and a lock shaft 18 pierces the door and is positioned eccentrically of the door, the outer end of the shaft being provided with the usual handle 19.

The shaft 18 is provided with spaced shaft rims 20 which retain the shaft upon the door, one of them being integral with the shaft and the other screw-threaded thereon. The inner end 21 of the shaft has slightly flattened faces, is reduced in size and is threaded to receive thereon in rotatable relation a suitable nut 22 and above the latter an actuating disc 23 having a squared, central opening 24 to receive the end of the shaft non-rotatably. 70 The locking device 25 is more or less conventional, it having the character of the usual combination lock and including means for thrusting a small bolt forward into the "throw" of the locking disc by the lock shaft 75 26, there being the usual combination dial 27 attached thereto on the outer face of the door.

When the door is closed, the locking bolts 17 engage suitable sockets in the receptacle walls, the bolts being provided with oblique 80 outer ends 28 in the conventional manner. The inner ends of the bolts are also provided with flattened surfaces 29 in a plane parallel with the face of the door, and are further provided with cross openings 30 in each at right 85 angles to such surface to receive therein pins 31 loosely for connection with a series of links 32, one in each, but permitting removal of said links from the bolts toward the center of the safe by withdrawal of the pins from said 90 openings.

The inner edge of the door 10 about the cavity 16 is provided with a series of locking pins 33 seated in pin wells 34 which extend at right angles to the face of the door and are 95 positioned closely adjacent the bolts 17 and at right angles thereto, each of the bolts having an annular groove 35 about it in proper position to hug the pins 33 when the latter are seated therein. An inward thrust of the said 100

pins will lock the said bolts against outward thrust or withdrawal, as will be hereinafter explained.

On the outer surface of the disc 23 are provided locking pins 36 so arranged that the rotation of the disc will cause them to encounter the locking bolt 37, if the latter is thrust outward from the lock 25, as by manipulating the combination. On the inner surface of the door, is provided a thin sheet steel cover 40 for the cavity 16, upon which the connection of the disc with the bolts 17 solely depends, since there is provided no other positive means for retaining the links in position. The inner surface of the disc 23 is provided with upstanding pins 38 adapted to receive the several links in apertures 39. The rotation of the disc will therefore actuate the bolts when the links are connected with the pins 38 and by means of the pins 31. It is the design of the links that they shall be readily detachable from both the disc and the bolts.

In ordinary operation, the bolts 17 will be withdrawn from their sockets in the wall of the safe, by the actuation of the links 32 through the operation of the disc 23. However, each of the pin wells 34 receives therein, first, a coil spring 42 usually fitting the well, and thereupon two locking pins 33 which, by the action of the springs, are normally thrust out above the inner surface of the door, but which, when the steel plate 40 is attached, will press the said pins down into the wells in position to permit the bolts 17 to be actuated.

The pins 33 are arranged in the wells in pairs, each pin having one pointed end 41 and the two pins seated in the well in opposing relation, the pointed ends being in contact intermediate the ends of the well. The pointed end 41 is so fashioned that it is well adapted to hug the groove of the bolt when thrust upward by the spring.

The plate 40 is normally attached to the inner face of the door by screws 43 thereby pressing the pairs of locking pins 33 down into wells 34, in which position the connection between the pins of each pair provides space to permit the bolts 17 to be actuated in either direction, the upward thrust of the pin normally in contact with the cover 40 releasing the lower pin by the force of the spring 42, whereby the pointed end 41 will be thrust into the groove 35 of the bolt and lock it in position. No means is provided for releasing such lower pin from the groove save the downward thrust of the upper pin with its point 41 in contact with the point of the lower pin. It will thus be evident that the release of the steel cover 40 will lock all the bolts 17.

Operation: The door 10 is mounted upon its hinges in position to fit the opening in the wall. The bolts 17 are fitted in position in the door openings and suitably connected by

the described links 32 with the actuating disc 23. The several springs and pins are fitted in the described pin wells 34 after which the plate 40 is screwed down upon the cone locking the pins 33 in inoperative position relative to the bolts. When the door is closed, a turn of the handle 19 will thrust the bolts 17 upward into their wall socket, when a turn of the combination shaft 26 will thrust outward the bolt 37 and by contact with the pins 36, lock the disc 23 against rotation until the bolt 37 is withdrawn by operating the combination in the usual manner.

It is well understood that a common means of safe breaking consists in drilling an opening through the door into the cavity 16, inserting dynamite into the cavity and blowing the charge in the hope that the shaft 18 will be operative after the charge has been exploded. On the contrary, such a charge will serve to remove the plate 40 and release the pins 33.

The release of the pins 33 will lock the bolts 17, as before explained, and the same explosive force that removes the plate 40 will also blow the several links 32 out of connection with the disc and bolts, since the pins 38 are readily removable from the opening 39 and the pins 31 from the openings 30. The removal of the plate 40 and links 32 therefore, destroys the connection of the bolts with the disc and at the same time locks the bolts against withdrawal. The plate 40 is made thin to make ready removal possible by an ordinary charge.

It is obvious that a number of variations may readily be made in this safe construction without forfeiting any of the advantages of the invention. The door may be provided with fewer or a greater number of bolts and a corresponding number of links 32. Such obvious variations are contemplated and are hereby made of record.

Having thus fully described my said invention, what I claim as new and desire to secure by Letters Patent, is:

1. A burglar-proof safe including a door having an inner socket and locking bolts movable lengthwise for engaging the safe wall when the door is closed, each bolt having an annular groove about its intermediate ends, a rotatable actuating disc within said socket and a crank shaft piercing said door and bearing said disc thereon in fixed relation, there being elongated members movable in said door adjacent the said grooves and normally pressed into locking engagement with said grooves, detachable means for covering the said socket and pressing said members out of engagement with said grooves, and detachable means for connecting the bolts with the disc.

2. A burglar-proof safe including a door having an inner socket and locking bolts for engaging the safe wall when the door is

- closed, the said bolts extending into the said socket, and each of them having an annular groove about it intermediate its ends, a rotatable actuating disc seated in said socket and 5 a crank shaft piercing said door and carrying the said disc on its inner end, there being elongated members movable in said door adjacent the said grooves and normally pressed into locking engagement with said grooves 10 yieldingly, detachable means for covering the said socket, and detachable links connecting the said disc with the several locking bolts, the said covering means serving to press the several members out of engagement with said 15 grooves and to normally prevent the links from being detached from the disc and bolts.
3. A burglar-proof safe including a door having an inner socket and locking bolts movable in said door for engaging the safe wall 20 when the door is closed and having their inner ends seated in said socket, a rotatable actuating disc seated in said socket and a crank shaft piercing said door and carrying the disc on its inner end, means for oper- 25 atively connecting the several bolts with the disc, there being pin wells in said door adjacent the several bolts and locking pins seated in said wells, each bolt having an annular groove about it intermediate its ends and 30 positioned in the same transverse plane of the bolt with the said wells, when the bolts are in locking position, a coil spring in each of said pin wells normally pressing one of the pins into locking position in the groove 35 of the bolt, and detachable means for covering the said socket and pressing the pins down in said wells against the force of the springs and out of engagement with said grooves.
4. A burglar-proof safe including a door 40 having a locking bolt carried thereby and slidable therein for engaging the safe wall when the door is closed, the said door having means for actuating said bolt and provided with a rock shaft whose rotation is opera- 45 tively connected with said actuating means, there being pin wells in said door adjacent the said bolt and locking pins seated in said wells, the said bolt being further provided with an annular groove about its peripheral 50 surface intermediate its ends and positioned in the same transverse plane of the bolt with the said wells, when the bolts are in locking position in the safe wall, a coil spring in each of said pin wells normally pressing one 55 of the pins into locking position in the groove of the bolt, and a thin metal plate mounted upon the inner face of said door and serving to normally press the pins down in said wells against the force of the springs and out of 60 engagement with said groove, but which upon being fired by an explosive charge, will be torn from the door, releasing the said pins which will then be formed inwardly in said wells into locking engagement with said 65 groove in the bolt.
5. A burglar-proof safe including a door having an inner socket and a locking bolt carried by said door adapted to engage the safe wall when the door is closed and entering the said socket when the safe is unlocked, a rotatable actuating disc within the socket and a crank shaft piercing said door and carrying said disc on its inner end, an actuating link connecting the said bolt with the disc whereby the rotation of the disc will 70 actuate the bolt toward and from the safe wall, the said connection being readily detachable, there being pin wells in said door adjacent the bolt, and locking pins seated in said wells, the said bolt having an annular groove about it intermediate its ends positioned in the plane with said wells when the bolt is in locking position, the said pins having each one pointed end and there being two pins in each well and positioned therein with 75 the pointed ends in contact, and spring means in each well beneath the pins to normally force the lower pins into locking position in said bolt groove, and a cover plate for the inner face of said door which when attached 80 thereto holds the pins pressed down in said wells against the force of said springs in position released from said groove.
6. A burglar-proof safe including a door having a locking bolt carried thereby and 85 slidable therein for engaging the safe wall when the door is closed, the said door having means for actuating said bolt, there being a pin well in said door adjacent the said bolt, and a locking pin seated in said well, the said bolt being further provided with an annular groove about its peripheral surface intermediate its ends and adjacent the said well, when the bolt is in locking position, a coil spring in said well normally pressing 90 said pin into locking position in said groove, and a cover plate which when detachably attached to the inner face of said door, holds the pin down in said well against the said 95 spring in inoperative position relative to the said groove.
- In witness whereof I have hereunto set my hand this 20th day of July, 1928.
- ADON L. SMITH.
